UNITED STATES PATENT OFFICE

151,445

DESIGN FOR A MUSICAL TOY OR SIMILAR ARTICLE

Joseph Green, New York, N. Y.

Application April 24, 1947, Serial No. 138,589

Term of patent 3½ years

(Cl. D34—15)

To all whom it may concern:

Be it known that I, Joseph Green, a citizen of United States, residing at New York city, in the county of Kings and State of New York, have invented a new, original, and ornamental Design for Musical Toy or Similar Article, of which the following is a specification, reference being had to the accompanying drawing, forming part thereof.

In the drawing

Fig. 1 is a top plan view of a musical toy, showing my new design;

Fig. 2 is a bottom plan view, and

Fig. 3 is an edge view thereof.

I claim:

The ornamental design for a musical toy or similar article, as shown.

JOSEPH GREEN.
